COMBINED BUMPER AND GRILLE FOR
AUTOMOBILES

James H. Sipple, Royal Oak, and Ned F. Nickles, Detroit,
Mich., assignors to General Motors Corporation, De-
troit, Mich., a corporation of Delaware

Application October 7, 1954, Serial No. 32,577

Term of patent 7 years

(Cl. D14—18)

Fig. 1

Fig. 2

Fig. 3

To all whom it may concern:

Be it known that we, James H. Sipple and Ned F. Nickles, citizens of the United States of America and residents of Royal Oak and Detroit, Michigan, respectively, have invented a new, original, and ornamental Design for a Combined Bumper and Grille for Automobiles, of which the following is a specification, reference being made to the accompanying drawing, forming a part thereof.

In the drawing:

Fig. 1 is a front view of a combined bumper and grille for automobiles embodying our new design;

Fig. 2 is a top plan view thereof; and

Fig. 3 is a side elevation thereof.

The automobile and fragmentary portions thereof shown by means of broken lines are disclosed only for

We claim:

The ornamental design for a combined bumper and grille for automobiles, substantially as shown and described.
